TRADE MARK.

No. 2,238.

Patented Dec. 26, 1865.

DES. 2238

Wm. F. and Benj. F. Heyman of Pittsburgh, Penna.

Letters Patent No. 2238 Dated Dec. 26, 1865.

Design for a Trade Mark.

The schedule referred to in these Letters Patent and making part of the same.

To all whom it may concern:

Be it known that we William F. Heyman and Benjamin F. Heyman of the City of Pittsburgh, State of Pennsylvania, have originated and designed a new design for a trade mark, of which the following is a full, clear and exact description, reference being had to the accompanying drawings, making part of this specification:

The design we wish to use as a trade mark is the Monogram of the two letters C & W to be used on our Copenhagen Snuff manufactured by us arranged as shown in the drawing.

What we claim as our invention & desire to secure by letters patent is the design for a trade mark herein set forth & shown.
